UNITED STATES PATENT OFFICE.

FRED G. HOFFINE, OF KANSAS CITY, MISSOURI, ASSIGNOR TO HOME IRONING BOARD COMPANY, OF KANSAS CITY, MISSOURI, A CORPORATION OF MISSOURI.

IRONING-BOARD.

1,063,685.

Specification of Letters Patent.

Patented June 3, 1913.

Application filed August 6, 1912. Serial No. 713,514.

To all whom it may concern:

Be it known that I, FRED G. HOFFINE, a citizen of the United States, residing at Kansas City, in the county of Jackson and State of Missouri, have invented certain new and useful Improvements in Ironing-Boards; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to ironing boards, and more particularly to a board having a body portion stamped from sheet metal and provided with folding legs whereby the device may be arranged compactly for storing or shipping; the principal object of the invention being to provide a sanitary structure of substantial construction.

It is a further object of the invention to provide a board of this character having a stop for the loose leg member whereby the height of the board may be regulated, and a tray for supporting large articles, such as tablecloths or the like, to prevent same from becoming soiled by coming in contact with the floor while they are being ironed.

In accomplishing these and the other objects of the invention, I have provided the improved details of structure hereinafter described and illustrated in the accompanying drawings, wherein:

Figure I is a perspective view of an ironing board constructed according to my invention. Fig. II is a central vertical section of same, showing the auxiliary board in position for removal, in dotted lines. Fig. III is a bottom plan view of the board. Fig. IV is an enlarged detail perspective of a part of the board, showing the bead and the method of attaching the iron and cloth holders. Fig. V is an enlarged plan view of one of the leg stops.

Referring more in detail to the parts:— 1 designates the body of the board, which is preferably stamped from a single piece of sheet metal and has its edges turned up beneath the board to form a bead 2, which provides a smoothed edge, strengthens the board, and forms a channel within which

the iron and cloth holder rods may be projected.

55

Fixed to the vertical portion of the bead flange 2, at the large end of the board, are straps 3 which are spaced apart to receive the end of the main supporting leg 4 therebetween, a pin 5 being projected through the strap members and through the end of the leg to pivotally mount the latter, so that it may swing toward and from the board. The second leg 6 is bifurcated and straddles the first, as illustrated most clearly in Figs. 65 I and III; being preferably formed, as is the main leg, from a single piece of tubing, bent to form a stop head 7 and a contacting neck 8, which latter engages the main leg and is pivotally connected thereto by 70 means of a pin 9, the free ends of the piece being spread and beveled to set flush on the floor.

Fixed to the bead flange 2 at opposite sides of the board are stops 10 which are preferably connected with the bead by welding to form a substantially integral structure therewith, each of the stop members having a plurality of sockets 11 adapted to receive the relative end of the stop head 7 of the 80 free leg, to hold same and thereby retain the legs in operative position, the plurality of sockets providing vertically adjustability to the board, as by seating the head of the bifurcated leg in the first socket the board 85 will be held higher than when the head is in the second socket.

The bead flange 2 is apertured at the ends and sides of the large portion of the board, and projecting through said apertures is a 90 wire bracket 12, which serves as an iron holder, a like bracket 13, which serves as a support for a cup 14, and wires 15, which serve as racks for supporting towels or like small articles after they have been ironed. 95

The bifurcated leg 6 has laterally opening apertures 16 adapted for receiving the in-turned ends of the wire frame 17 which carries a receptacle for holding articles being ironed. The frame 17 is substantially 100 V-shaped, and has a post 18 pivotally connected therewith at the end opposite the in-turned ends which is adapted to project through an aperture 19 in the top of the main leg to support the frame in horizontal 105 position. The frame wire carries a cloth

20, which is slit at 21 to allow the side portions to hang at opposite sides of the main leg, so as to form a receptacle for supporting the ends of the tablecloth or like, which is 5 being ironed on the board, to prevent same from becoming soiled by coming in contact with the floor.

I have provided the device with an auxiliary or shirt board 22, which has a support 23 10 adapted to rest on the top of the main board, and has a strap 24 at the end which curves under the bead 2, and has a hook 25 adapted to hold beneath the bead.

It is apparent that the bracket wires may 15 be moved beneath the board when not in use, so that the structure will occupy less room, and may be pulled out when the board is to be used. It is also apparent that the receptacle may be easily and quickly removed from the board when the latter is to 20 be folded and that the shirt board being separate from the main board may be used only when required.

With a board of this construction the main 25 board may be padded and covered in the ordinary manner so that it provides a smooth surface, and by means of the folding legs

the entire device may be "knocked down" to occupy a very limited space when not in use.

Having thus described my invention, what I claim as new therein and desire to secure by Letters Patent, is:

An ironing board comprising a body member, a main leg pivotally connected with the 35 body member, a bifurcated leg pivotally connected with the main leg and adapted for engaging the body member, said bifurcated leg having laterally opening apertures, a leg having an upwardly opening aperture, 40 a tray frame comprising a wire having ends adapted for projection into the laterally opening apertures, and a post pivotally connected with the frame and adapted for projection into the upwardly opening aperture, 45 substantially as and for the purpose set forth.

In testimony whereof I affix my signature in presence of two witnesses.

FRED G. HOFFINE.
